US00D941172S

(12) **United States Design Patent** (10) **Patent No.:** **US D941,172 S**
Baldree (45) **Date of Patent:** **** Jan. 18, 2022**

(54) **MOBILE PHONE PERSONAL SECURITY ACCESSORY**

(71) Applicant: **Katana Safety, Inc.**, Greenville, SC (US)

(72) Inventor: **Todd W. Baldree**, Greer, SC (US)

(73) Assignee: **Katana Safety, Inc.**, Greenville, SC (US)

(**) Term: **15 Years**

(21) Appl. No.: **29/696,313**

(22) Filed: **Jun. 26, 2019**

Related U.S. Application Data

(63) Continuation of application No. 29/692,014, filed on May 21, 2019, which is a continuation of application No. 29/618,024, filed on Sep. 18, 2017, now Pat. No. Des. 853,400, which is a continuation of application No. 15/642,267, filed on Jul. 5, 2017, now Pat. No. 10,111,079.

(60) Provisional application No. 62/358,996, filed on Jul. 6, 2016.
